FIG. 1 is a perspective view of a high intensity lamp illustrating my new design;

FIG. 2 is a front elevational view of the same;

FIG. 3 is a side elevational view of said lamp;

FIG. 4 is a rear elevational view of said lamp;

FIG. 5 is a perspective view of said lamp with the shade collapsed on the base in a stowed position of the lamp; and

FIG. 6 is a side elevational view of said lamp in its stowed position.

The dominant features of my design reside in the portions shown in full lines.

I claim:

The ornamental design for a desk lamp, as shown and described.
